UNITED STATES PATENT OFFICE.

JOHN HOWARD LUFKIN, OF SPRINGPORT, MICHIGAN.

HOUR-HAND MOVEMENT FOR TIME-PIECES.

SPECIFICATION forming part of Letters Patent No. 316,798, dated April 28, 1885.

Application filed November 10, 1884. (No model.)

To all whom it may concern:

Be it known that I, JOHN HOWARD LUFKIN, a citizen of the United States, residing at Springport, in the county of Jackson and State of Michigan, have invented a new and useful Improvement in Hour-Hand Movements for Time-Pieces, of which the following is a specification.

My invention is applicable to both clocks and watches, and relates to the movement of the hour-hand. Its object is to have the hour-hand point directly to the hour instead of being between the spaces, as is usually the case. The new appliance takes the place of the combination of cog-wheels usually in front and outside of the frame of the inner works, known as "hour" and "minute" wheels, and is illustrated by the accompanying drawings.

Figure 1 is a clock-front with the dial cut away, showing the parts combined as if in operation; Fig. 2, a curved spring, to one end of which is fastened a socket, B, which goes onto the center arbor firmly, so that it turns with the minute-hand, and to the other end a short pin, A, extending forward at right angles over the hour-wheel and so adjusted as to just clear the outside in passing round; Fig. 3, the hour-wheel, which has twelve notches instead of cogs, and is otherwise the same as the common hour-wheel; Fig. 4, a straight spring fastened to the inner frame by a post, C, and bearing on a notch of the hour-wheel D.

H, Fig. 2, represents a curved spring. The position of the spring H is such that the pin A is opposite the minute-hand. As it moves onward it will come against the spring C D,

by means of which it will be pressed downward and into the notch F, carrying with it the hour-wheel, also the hand, so long as the pin remains beneath the spring, or one-twelfth 40 of a revolution. The hour wheel and hand will begin to move when the minute-hand has reached twenty-seven and one-half minutes past, so that when the minute-hand is at half-past the hour-hand will be midway between 45 the hours, and when the minute-hand is at twenty-seven and one-half minutes of the hour-hand will stop on the next hour and remain there until the process is repeated.

It may be claimed by some that by the old 50 way the hour-hand, by its position between the hours, helps also to indicate the minutes; but such is not the case. The hour-hand has no more to do with minutes than the minute-hand with hours. We see by the minute-hand 55 in Fig. 1 that it is twenty-five minutes past some hour, then looking at the hour-hand we see that the hour indicated is two.

I claim—

A ratchet-wheel secured to the hour-hand 60 arbor of a time-piece, and the spring-arm H, secured to the minute-hand arbor, and having a pin on its free end at an angle thereto, in combination with the spring D, secured to the frame of the time-piece, the said spring 65 and wheel being arranged to move the hour-hand at the required intervals, substantially as described.

JOHN HOWARD LUFKIN.
